UNITED STATES PATENT OFFICE

2,064,484

COKING APPARATUS

Joseph V. Meigs, Hastings-on-Hudson, N. Y., assignor to The Barrett Company, New York, N. Y., a corporation of New Jersey

Application April 27, 1929, Serial No. 358,645
Renewed June 8, 1934

13 Claims. (Cl. 202—134)

This invention relates to the distillation and carbonization of substances, particularly bituminous materials, including coal tar pitch and other pitches, asphalts, petroleum residues and the like and provides improved apparatus for such carbonization and distillation.

Numerous attempts have been made to provide practically successful means for carbonizing pitches at low cost for labor, upkeep and other charges, for producing satisfactory coke and for recovering the by-products.

The ordinary by-product coke oven is not well adapted for the purpose. The intumescence and frothing of the material during its conversion from the melted condition to the solid one, or to coke, may cause the charge to be ejected through the various openings, such as the uptake pipe and charging holes.

Petroleum coke and pitch coke may be made in iron or steel stills, but the method is attended with numerous disadvantages, such as rapid depreciation of the apparatus, loss of time in cooling the charge and difficulty in removing it from the still.

In efforts to overcome the difficulties experienced in carbonizing pitches, asphalts and the like in large masses it has been proposed also to carry out the carbonization in small pots; to flow oil residuum, wax tailings, etc. down the inside surfaces of a tower counter current to a stream of hot combustion gas; to carbonize pitch in films in apparatus somewhat similar to a drum dryer; to mix pitch with non-combustible material and run the mixture through a rotating cylindrical still resembling, in part, a rotary kiln; and to carry out other processes which seek a solution of the problem of producing pitch coke and recovering the by-products of the coking process, at sufficiently low cost and in such manner as to render the process attractive from the financial, commercial and technical points of view.

The present invention provides improved process and apparatus whereby pitch and analogous materials may be carbonized in upright, relatively narrow, horizontally elongated chambers or ovens, whereby the ebullition or intumescence of the material is provided for.

It furthermore provides means whereby the bituminous material may be charged into the hot ovens immediately upon discharge therefrom of the previously produced coke, without the intervention of a cooling period.

It provides improved means whereby the pitch may be thoroughly carbonized in large masses,

freed of volatile matter and converted into hard, strong, massive coke in a relatively short period of time.

It provides improved means for obtaining and handling the volatile by-products whereby increased yields of the vapors of oils and solid materials may be obtained, purified and condensed and means whereby the pressure in the coking chambers may be kept uniform and whereby the charging of bituminous material is facilitated.

It provides improved means whereby the coke tenaciously adhering to the interior surfaces of the heating walls may be removed by a carbon-consuming gas, such as highly heated steam, as a result of which the coke charge may be readily ejected and whereby useful gas is produced. It provides improved means for removing volatile products from the pitch and coke and for recovering the same.

In using the apparatus bituminous material is charged into a group of horizontally elongated, relatively narrow, upright coking chambers communicating freely with each other through a relatively wide space at the top of the chambers common to all the chambers of the group. Heat is applied to or maintained at the sides of the chambers to distill and carbonize the bituminous material and drive off gases and readily condensable vapors, and the latter are removed, under carefully controlled pressure conditions, from the coking chambers and the common communicating and expanding space lying above the same and treated to recover valuable products. Gas and vapor are driven off from the bituminous material and the mixture of the same with liquid bituminous material may travel more or less rapidly up through the narrow chamber spaces.

Upon reaching the space above the chambers the upward movement is retarded and separation of gas and/or vapor and liquid or plastic bituminous material may be effected. The narrow chambers may be charged to somewhat less than their capacities; or some of the chambers may be fully and others less fully charged; or some may be fully charged and others not charged at all, so that bituminous material may foam over or be transferred through the space lying above the chambers from the more fully charged chambers into those less fully charged or not charged. When foaming has subsided additional bituminous material may be charged into any of the narrow chambers and distillation and carbonization continued so that at the end of the coking cycle all the narrow chambers may be fully charged with coke.

At the end of the coking process, doors at

the ends of the group of chambers are removed and the coke is discharged horizontally.

Between the individual coking chambers of the group of such chambers, horizontally elongated heating structures are located having, in sections thereof at right angles to the horizontal axis of the coking chambers, an inverted U or inverted V shape or modifications of such shapes. These heating structures are adapted to be heated from the inside and the invention comprises the process of heating such structures, regulating the heating thereof and flowing melted bituminous material over the outside surface thereof, distilling, solidifying and carbonizing the bituminous material and building up layers of carbonized material on the vertical or inclined surfaces of the said structures.

From the apparatus standpoint the invention comprises, broadly, horizontally elongated upright or vertical coking chambers alternating with similarly disposed flue-chambers or heating elements, combined into a group, and combinations of such groups. The individual coking chambers of each group are in free communication through a common space above the said chambers and the vertical longitudinal sections of the said common space are preferably substantially greater than the horizontal section of any individual coking chamber.

In addition to the general features and provisions recited above, the invention includes such further provisions, objects, improvements and advantages as are found to obtain in the processes, structures and devices hereinafter described, shown or claimed.

The invention will be described more particularly with reference to the accompanying drawings, which form a part of the specification and which illustrate certain embodiments of the apparatus of the invention and of means for the practice of the processes thereof. It is intended and will be understood that the invention is illustrated by and not limited to the specific embodiments so illustrated and described.

Figure 1 represents an enlarged vertical section transversely of the coking chambers through a portion of a combination of groups of coking chambers, taken on the lines D—D of Figure 3 and E—E of Figure 2.

Figure 2 is a vertical section on the line A—A, Figure 1, with the doors at the ends of the coking chambers removed, showing fuel gas supply header pipes in elevation.

Figure 3 is a vertical transverse section on the line B—B, Figure 1.

Figure 4 is an enlarged horizontal partial section on the line C—C of Figure 1.

Figure 5 is a partial vertical section on the line E—E of Figure 4.

Figures 6 and 7 are vertical sections taken transversely of the coking chambers and showing modified forms of the structure shown in Figures 1, 2, and 3.

Figure 8 is an elevation, partly in section, of one end of a coking chamber showing an uptake pipe for removing volatile products from the chamber, a purifying device, a pressure regulating device, conduits for gases and vapors, condenser and gas pump or exhauster.

The figures are more or less diagrammatic and like parts are designated by like numerals.

1A, 1B, 1C, and 1D represent in section coking chambers with heating walls 3 and 6A and soles 12. The walls 3 enclose and contain vertical

heating flues 15, as shown in greater detail in Figure 3, and support the arches 2. The flues 15 are separated by partitions 14, which brace the walls 3. The partitions 14 and the walls 3 are in turn supported by the heavy walls 4, which extend longitudinally of the coking chambers from the wall 21, on the coke discharge side, to the wall 21A on the pusher side of the battery, as shown in Figure 3. The heavy walls 4 rest upon the mat or platform 5, which constitutes the sub- 10 foundation of the structure.

The coking chambers, as for example 1B and 1C, are separated by the structure 6. This comprises the walls 6A, which may be parallel to the walls 3, connected at the top by the arch 6B. 15 The walls 6A are secured in the base 26. The latter is supported by the walls 10 and 11, which like the walls 4 extend from front to rear of the ovens or coking chambers. The spaces between the walls 4, 10, and 11 contain regenerators, as more 20 fully described below. For the purpose of the present invention the coke discharge side of the ovens will be regarded as the front thereof and the pusher side as the rear.

The construction shown provides great 25 strength for the entire structure, as well as for its constituent parts including the structures 6. The walls of the latter possess great resistance to lateral thrust by virtue of their internal bracing, as will be described below, and through 30 their secure anchorage in the solid bases 26 and oven soles 12, said bases 26 and soles 12 being adequately supported on the walls 10, 11, and 4.

The structures 6, one of which is shown in Figure 2 in a vertical section taken in a plane substantially parallel to the walls 3 and 6A, extend from front to rear of the coking chambers. They are closed at the ends and these ends, 21C and 21D, are substantially flush with and form a part 40 or extension of the corresponding front and rear walls of the battery, 21 and 21A, respectively. The structures 6 are braced internally by the vertical walls 9 anchored in the bases 26, and by horizontal members 8. The latter are arranged in 45 staggered formation, as shown in Figure 2, forming horizontal flues 7 which communicate with each other and with regenerators 27 and 28.

There are two sets of horizontal flues 7, one set on each side of the wall 9, and corresponding 50 to and communicating with each set of flues there are a pair of regenerators 27 and 28, as shown in Figure 2. The pairs of regenerators are separated by the wall 11 and the individual regenerators of each pair are separated by the 55 vertical wall 29 and the baffle 33. The walls 29 connect and brace the walls 10 and 11 and are substantially at right angles to the same. The walls 29 do not extend all the way up to the base 26 and stop at the arches 29A, which form, with 60 the horizontal baffles 33, passages 31 constituting continuations of the passages 30, said passages 30, 31, and 32A constituting respectively direct communication between the regenerators 27 and the lowermost of the twin series of flues 7 on either 65 side of the walls 9.

In addition to the horizontal flues 7 two vertical flues 31, each of which communicates directly with one of the uppermost horizontal flues 7, are formed by the walls or partitions 33A which connect the walls 6A and 9. Each of the flues 31 70 communicates also directly with one of the regenerators 28 through openings 32 in the base 26. A baffle 39 extends under a portion of each of the regenerators 28 to give proper direction to the 75

gases passing therethrough. Ports 25 and 25A under the regenerators 27 and 28 serve for the passage of air or waste gas into and out of the regenerators, respectively.

5 The flues 7 and 37 are provided with fuel gas by nozzles 38 which communicate through valves 35 with fuel gas supply headers 34 and 34A. The nozzles 38 extend from the valves 35 through the brick end walls 21C and 21D. The nozzles passing through the wall 21D pass also through the flue 37 and the wall 33A. The portions of those nozzles which extend through the flue 37 are covered with insulating material 36 to protect the nozzles from the action of highly heated combustion gas.

10 The temperature in the individual flues can be regulated by adjustment of the gas valves 35, which are located outside the ends of the structure 6 and are therefore readily accessible from 15 a position outside the coking chamber.

15 Each series of flues, one series on each side of the walls 9, are provided respectively with gas supply headers 34 and 34A, gas valves 35 and nozzles 38. This provides numerous points of 20 temperature control so that the walls 6A of the structures 6 may be heated to different temperatures at different points thereof. In the particular arrangement shown, there are sixteen individual flues for each of the structures 6 and 25 therefore sixteen zones of temperature control, each individually controllable by manipulation of the valves 35 located outside the coking chambers.

20 Fresh air to maintain combustion of fuel gas 35 in the flues 7 and the flue 37 is alternately supplied to regenerators 27 and 28. Likewise waste products of combustion from the flues 7 and the flue 37 are passed alternately through regenerators 28 and 27, whereby heat is stored up in those 30 regenerators and then imparted to the air for combustion that passes through the same. Subterranean conduits or mains not shown, one on each side of the battery, serve to alternately supply air and to withdraw waste gas from the regenerators in the manner known in the art.

35 For example, air is supplied to the regenerator 27 from a main (not shown) through the port 25, passes through the checkerwork, through the passage 30, over the baffle 33, through the opening 32A, through the flues 7 and the vertical flue 37, and then passes through the checkerwork in the regenerator 28 to the port 25A and finally to a waste gas main (not shown). Combustion takes place in the flues by means of fuel 40 gas supplied as described above.

45 At the end of a suitable period, for example one half an hour, the air supply is reversed. It is then supplied from the waste gas main last mentioned above to the port 25A, and passes through the heated checkerwork in the regenerator 28, through the opening 32, through the flue 37, the flues 7, the opening 32A, the passages 31 and 30, through the regenerator 27 and finally to the main, via the port 25.

50 The walls 3 contain vertical flues 15 communicating with the horizontal top or bus flues 16. Under the sole of each coking chamber a pair of regenerators 23 and 24 are situated. The members of each pair are separated by the walls 20B located between the individual regenerators 55 of each pair. The walls 20B extend from the base 5 up to the soles 12 and not only separate the regenerators 23 and 24 but also assist in supporting the soles 12 and the adjacent structures 60 and in bracing the walls 4 and 10. The pairs, 23 and 24, of regenerators are on opposite sides of the walls 4 and each pair communicates with each of the flues 15 through ports 18. Each flue 65 may communicate also with one of the gas mains 20 and 20A through ports 19.

70 Combustion in the flues 15 may be effected by the use of regeneratively preheated air, and coke oven gas or other gas with a high heating value, such as gas produced by the carbonization of pitch, asphalt or petroleum residues. Combustion may also be carried out by using regeneratively preheated air and regeneratively preheated gas such as producer gas, blast furnace gas or other gas with a low heating value, with a corresponding release for other purposes of the 75 more valuable gas made by the carbonization process.

75 Combustion in the flues 15 takes place in only one half of those flues at one time, viz. that half which is on one or the other side of the 80 wall 20B and superlying partition 14. While combustion is taking place in an upward direction in one half of the flues, the products of combustion pass downwardly through the remaining half of the flues into the regenerators 25 below and on either side of that half.

85 Assuming, for example, that coke oven gas is to be employed for heating purposes, this is supplied through the conduit 20 to the flues 14 above the conduit 20 through ports 18. Assuming also that regenerators 23 have been heated by previous passage through them of hot combustion products, air is supplied through ports 25, passes upwardly through regenerators 23 and the ports 18 communicating with those regenerators and burns the coke oven gas supplied from the conduit 20. The products of combustion pass through the overhead bus flue 13 downwardly through the other half of the flues 15 and ports 18, downwardly through regenerators 40 24 and are educted through ports 25A. During this time, fuel gas is turned off from the fuel gas main 20A. At the end of a suitable period, such as one half hour, the direction of air and fuel gas is reversed. Fuel gas is turned off from the conduit 20 and turned on in the conduit 20A and air is supplied to the regenerators 24 through ports 25A. Combustion now takes place in that half of the flues above regenerators 24, flames move upwardly in these flues, and the combustion products pass through the flue 13 and then downwardly through the other half of the vertical flues and through the regenerators 23 and are educted through ports 25.

90 If a gas such as producer gas is to be employed for heating purposes, the mains 20 and 20A are valved off. One member of each set of regenerators under the sole of the coking chambers is then alternately used for preheating producer gas supplied to it through its port 25 and 95 the corresponding regenerator of the other set, on the other side of the wall 4, is simultaneously used for preheating air.

95 The means for supplying producer gas and air to the ports of the regenerators and richer 100 gas to the mains 20 and 20A, for educting the products of combustion from the regenerator ports and for reversing the supply of fuel gas and air are not shown. By the means described and shown the walls 3 may be heated, optionally, by producer gas, by the gas made as a result of the coking process or by ordinary coke oven gas. This permits the conservation of a large 105 part of the gas made by the coking process de-

scribed below, which, in many cases, possesses a high heating value.

The size of the openings in the ports 18 and 19 may be adjusted by the use of suitable plugs or nozzles and those openings may be completely covered by the use of closure bricks, not shown. By the use of such closure bricks on the bottom of the flues and closure bricks 16A on the top thereof, any flue or group of flues may be put out of operation or the draft in any flue may be controlled. By the means described the temperature in each flue is subject to control. Access to the bottom of the flues 15 and the plugs and closure devices of the ports 18 is had through the passages 17 and bus flue port holes 17A by means of a rod thrust down through these openings. The port holes 17A are closable by sliding bricks 16B and the passages 17 may be closed at the top thereof by bricks properly shaped and resting upon the shoulders shown in Figure 3. Access to the bus flue 16 may be had through holes 16C normally closed with suitable closures.

The soles 12 of the coking chambers, as shown in Figures 1, 4, and 5 and, in modified form, in Figure 6, are specially constructed to permit the admission of gases, as for example, superheated steam, as described below. Figure 4 represents a partial plan view and Figure 5 a vertical section of the sole of an individual coking chamber and adjacent parts. The sole 12 is securely anchored in the brick work lying underneath it and is separated from the walls 3 and 6A by narrow slits 47. Rectangular recesses 43, forming a pair of horizontal conduits, extend from one end of the sole to the other and each conduit communicates with the adjacent wall through apertures 46. Perforated pipes 45 made of heat resistant metal extend through the conduits 43, the perforations facing the apertures 46 and being adapted to deliver gas through them. The conduits 43 extend to within about one foot of each end of the oven soles 12. The ends of the conduits near the wall 21A are closed, preferably by removable closures so that access may be had to the conduits at those ends for cleaning or other purposes. The ends near the wall 21 communicate with recesses 49 in the bases 26 of the structures 6. Valved pipes 50 extend through the wall 21C of the structures 6 into the recesses 49 and communicate therein with pipes 45 to deliver steam or other gas, as desired, to said pipes 45. The slits 47 extend substantially the same length of the soles 12 as the conduits 43.

The coking chambers, for example 1B and 1C, are provided at each end with removable doors (not shown) which are removed when the charge of coke is to be pushed and are secured in place and suitably sealed prior to charging and carrying out the coking cycle. The doors may have an inverted U-shape corresponding to the shape of the section of the coking chambers, e. g. 1B and 1C, and the space above connecting the same. They are removed, e. g., in the manner customary for removing coke oven doors, prior to the pushing operation and are secured in place and adequately sealed prior to carrying out the coking process or cycle, so that leakage may not occur during the charging and coking operations.

The tops of the coking chambers or arches 2 contain charging holes 42 for solid bituminous material, constructed and provided with closures in the usual manner. Valved nipples 41 for the admission of steam or other suitable gas and larger valved nipples 40 for the admission of melted bituminous material are also provided,

in multiple series, as shown in Figures 1 and 2.

The dimensions of the coking chamber may be varied to a large degree. As a specific example of dimensions, the width may be eighteen inches, the length twenty-five feet and the height ten feet. By height is meant the perpendicular distance from the soles 12 to the top of the arches of the structures 6. The maximum vertical width of the spaces 2A may be four feet. The transverse widths of the structures 6 may be four feet. It is desirable that the width of the structures 6 be substantially greater than the width of the coking chambers, in order that the structures 6 may possess sufficient strength and resistance to lateral thrust. While the present invention provides means for greatly reducing the pressure on the structures 6 and walls 3 (particularly during the pushing operation) by providing means for "cutting" the coke charge away from the retaining heating walls as described above, there may be cases where it is not desired to carry out the said "cutting" or coke consuming operation and in such event the walls 3 and structures 6 must be sufficiently stiff and strong to withstand any pressure encountered during pushing. Undue length of the coking chambers and structures 6 should be avoided to avoid undue difficulty and undue stresses during pushing.

As shown in Figures 1 and 2, the coking chambers, as for example 1B and 1C, freely communicate with each other through the space 2A above those chambers. The widths of the space 2A, that is, the varying distances between the arch 6B and arch 2, are greater than the width of the chambers 1B and 1C (which is the distance between the walls 6A and walls 3). The space 2A thus provides an expansion chamber between the communicating chambers 1B and 1C and is substantially co-extensive horizontally with said chambers.

The elements of the structure shown in Figures 1, 2, and 3 cooperate in a combination to provide structural and operative improvements. The walls 4, 3, 10, and 11, arches 2 and bases 26, as well as the bracing and dividing walls 20B and 29 are combined, the parts of which cooperate to brace and strengthen each other and to provide secure foundations 26 for the heating elements 6. The latter, as shown in Figure 1, stand alone, may be subject to great lateral or side-wise thrust during the pushing operation and are therefore not only thoroughly braced internally but also securely anchored externally in heavy bases 26, which derive strength from the structure as a whole as well as from the immediately adjacent parts.

The invention is not however limited to the specific details of structures and methods described or shown herein. For example, other arrangements of flues and regenerators, consistent with suitable strength and control of the coking and gas making processes, may be employed. The heating flues in the structures 6 may be vertical instead of horizontal and means may be provided to supply such flues with regeneratively preheated lean gas such as producer gas.

The portions of the structures herein described or shown that are subject to contact with highly heated gas are preferably made of high grade refractory material such as silica brick.

In order to further increase the strength of the structures 6, these may be re-enforced by alloy steel, capable of retaining its strength at

high temperatures, embedded in the walls 6A and anchored in the bases 26.

Figures 6 and 7 show modified forms of coking chambers. In Figure 6, the arch 53 is supported 5 on walls 57, which are, preferably, supported by heavy walls (not shown) similar to the walls 4 in Figure 1. The walls 57 enclose heating flues 58 which may be horizontal or vertical. The central heating structure 60 is shown as heated 10 by horizontal flues 59. The walls of the structure 60 are, preferably, supported on heavy foundation walls (not shown). The coking chambers 98 and 99 formed between the structure 60 and walls 57 have a pronounced taper 15 from top to bottom, as clearly shown. This particular form of construction is correlated with the practice of one form of the process of the invention, as will be explained below. The oven shown in Figure 6 is provided with charging holes 20 above the coking chambers as indicated at 56, for solid bituminous material, and with a double series of valved nipples 54, for charging melted bituminous material, only two of which are shown. The soles 12 conform to the taper of the 25 walls adjacent thereto, and are constructed to perform gas- or steam-admitting functions in a manner similar to that described in connection with Figures 1, 2, 4, and 5.

In Figure 7, two structures, 61 and 62, containing heating flues form, together with walls 74, three coking chambers, 70, 71, and 72 communicating with each other through the common space beneath the arch 75, which acts as a communicating and expansion chamber. The 30 walls 74 contain heating flues which may be vertical or horizontal and are shown as vertical flues. The structures 61 and 62 may as shown be joined by the brick work or wall 76. This greatly strengthens these structures and provides 35 great resistance to lateral thrust upon the same. The chamber 71 augments the expansion and communication space described above. Charging holes 63 are provided for solid bituminous materials and a series of valved nipples 66A, 66B, 40 67A and 67B, only four of which are shown, for melted bituminous materials. The heating flues in the walls 74 preferably communicate with twin sets of regenerators (not shown) located under the coking chambers 70 and 72, respectively, in the manner described above with reference to the flues 15 and regenerators 23 and 24 in Figures 1 and 3. The heating structures 61 and 62 are provided respectively, as shown, with horizontal flues communicating respectively with 45 sets of regenerators (not shown) under each series of flues in the manner shown in Figures 1 and 2 and described above with reference to the respective sets of regenerators, 27 and 28, under each respective series of horizontal flues in each structure 6. The various flues in the walls 74 may be supplied with rich or regeneratively heated lean fuel gas in the manner described for heating the flues 15, as hereinabove described in connection with Figures 1 and 3, and the flues in the structures 61 and 62 may be supplied with fuel gas as shown and described with reference to Figure 2.

Instead of the single heating elements or structures, 6, or double elements, 61 and 62, multiple heating elements may be employed. For example, three, four or even more of such heating elements may be used. These may have the shape shown in Figures 1, 6 or 7, i. e., an inverted U-shape or inverted V-shape, in sections taken 75 at right angles to the long axis of the coking

chambers. The heating elements enclose heating flues and the group of elements and the group of coking chambers formed thereby are enclosed by elongated walls, such as 3, or 14, or 57, and by the arches supported by the said elongated 5 walls. The heating elements may be braced by solid walls between them as shown in Figure 7.

Figure 8 illustrates diagrammatically in end elevation, partly sectional, means for removing and recovering distillates, such as oil and gas 10 produced by the destructive distillation of bituminous materials. The uptake pipe 77 communicates with the opening 13 and the pipe 79. The latter leads into the expansion chamber 80, provided with clean out doors 86 and draw-off 15 pipe 91 in which valve 96 is located. Spray means 90 connected with valved supply pipe 91 is located in the upper part of the chamber 80. Pipe 81 leads from the chamber 80 to the condenser 82, provided with draw-off pipe 84 for 20 condensed material, said pipe 84 being provided with a suitable valve, not shown. The exhauster 83 is adapted to exhaust gas from the condenser 82 and to deliver it to storing and/or purifying means (not shown). 25

In order to care for large volumes and surges of vapors produced during distillation and carbonization of bituminous materials such as asphalt, pitch, et cetera, the pipes 77, 79, and 81 30 are made of ample size and a butterfly valve 95 35 is located in the pipe 81 and is adapted to be operated by the motor 94 working in conjunction with the pressure control device 93 which communicates through pipe 92 with the pipe 81A. The exhauster 83, valve 95 and pressure control 40 device 93 are adapted to operate to maintain pressure in the coking chambers substantially at atmospheric pressure at all times during the coking period or cycle. To further assist in carrying out this object, a plurality of openings 13 45 with corresponding uptake pipes 77 may be provided at more or less regular space intervals distributed in the arches 2 above and aligned with the structures 6 and connected together by means of a header leading to the chamber 80. In the drawings only one such opening 13 and uptake pipe 77 is shown.

The chamber 80 may be individual to each pair or group of communicating coking chambers as shown in Figure 8, or may be common to 50 a series or battery of coking chambers. The valve 87, operated by the spindle 88 and handle 89, controls communication between the chamber 80 and the coking chambers connected with the pipe 79. The spray means 90 is adapted to 55 receive from the pipe 91 either liquid or gaseous materials, for example, superheated steam or heated liquids such as condensate from condenser 82, and to deliver such materials as a spray into the gas stream from the pipe 81B. 60

The practice of the process of the invention in its various forms may be carried out with a variety of bituminous materials, such as native asphalts including Gilsonite, petroleum residues and pitches, coal tar pitches, et cetera. In practicing the process of the invention, assuming that coke has just been pushed from the coking chambers, as for example 1B and 1C, that these chambers are in a highly heated condition; that the doors at the ends of the coking chambers have 70 been put in place and made tight, that the valve 87 is closed, and that pitch from coke oven tar is the material selected for carbonizing, coke from a previous operation is charged through openings 42 in amount sufficient to cover soles 75

12 and slits 47 to a depth of about one foot. The openings 42 are then closed and valve 87 is opened. Melted pitch is then gradually charged, from a source (not shown) through the nipples 40, so that it strikes the top of the arch 6B and flows down the walls 9. By virtue of its contact with the highly heated structure 6, volatile material is removed from the pitch. By use of the regenerators 27 and 28 and by proper control of the air-gas mixture in the flues 7 by manipulation of the valves 35, the arch 6B and walls 6A are maintained at high temperature. The rate at which melted pitch flows down over those walls is then regulated by valves in the nipples 40 so that by the time the pitch reaches the layer of coke on the soles 12, the pitch has become solidified to such an extent that it is not capable of penetrating the coke layer and not capable therefore of clogging the slits 47. As this procedure is continued, layers of carbonized pitch gradually build up on the surface of the walls 6A.

After this procedure has supplied sufficient solidified or coked pitch to cover the coke layer on the soles 12 to a depth of six inches or one foot 25 or thereabouts, the melted pitch is more rapidly admitted through the nipples 40. The chambers, for example 1B and 1C, are however charged to different heights. The chamber 1B, for example, is charged to a height about opposite to the highest 30 of the flues 7 in the structure 6, while the chamber 1C is charged to only about one half of this height. This is done by adding pitch to a greater or lesser extent through one or the other of the sets of nipples 40 positioned, as 35 shown in Figure 1, on either side of the center of the arches 2.

Combustion is maintained in the flues 15, 7, and 37, and volatile material is progressively removed from the pitch, with concurrent foaming thereof to a greater or less degree. That portion of the charge which expands and foams over from, for example, chamber 1B through the expansion space 2A, is delivered into chamber 1C which was not previously fully charged. Expansion and foaming are, to a substantial extent 45 at least, due to the release of vapor or gas from viscous material and are therefore particularly active as the coking period approaches, when the material is approaching the solid stage and when 50 gas in large volumes is being evolved. The space 2A and the unfilled portion of the space 1C provide expansion and separating chambers where mixtures of gas or vapor and liquid material may be separated prior to the delivery of the gas 55 and/or vapor through the port or ports 13 into the by-product recovery system.

By means of the method and apparatus herein described, the pitch, instead of expanding up into the various charging holes and outlets and 60 clogging the same, has ample opportunity to merely pass from one coking chamber to another through a large communicating and expanding space. After the foaming or expansion has subsided, additional pitch may be added to 65 any coking chamber, i. e., 1B or 1C, so that at the end of the process, the coking chambers may be fully charged with coke.

During the period when expansion and foaming are taking place, steam or other suitable gas 70 may be directed downwardly upon the pitch from the nipples 41, to repress the foaming and to assist in making the resulting coke less porous. The steam or gas so used is preferably highly superheated.

At the end or shortly before the end of the 75

coking period, highly heated steam is supplied through valve 50 to the pipes 45 and conduits 43 and is delivered through the slits 47, in the form of layers of steam. The object of this step is, in part, to clean or scour the walls of the coking chamber by consuming and converting into useful fuel gas the coke immediately adjacent to the walls of the coking chambers, thus facilitating the release of the coke charge from the walls during the pushing operation and decreasing the pressure exerted on the walls of the structures 6. For this purpose any gas may be used that will react with heated coke and convert it to a gas, such as steam or carbon dioxide. From the point of view of convenience in the 15 use and in the disposal of an excess thereof, steam is preferred. In addition to the "scouring" action which it has on the walls of the coking chamber, it also forms useful "blue" gas by reaction with the coke film or layer immediately 20 adjacent to those walls and such gas together with excess steam assists in removing volatile matter from the coke and producing an improved coke. Coke made by carbonizing fusible bituminous materials adheres, in many cases at least, 25 more firmly to the walls of coke ovens, retorts, etc., than coke made from coal and may therefore be more difficult to "push" than ordinary coke, and the present invention provides the means herein described for overcoming this 30 difficulty.

The admission of steam or other suitable gas need not be delayed until the end of the coking cycle but may also be effected during the distillation of the pitch to assist in the removal of the 35 volatile products therefrom.

The heavy grease-like and resinous matters evolved from bituminous material during the latter or final periods of distillation thereof are somewhat difficult to remove completely and the 40 use of steam or other suitable gas, as herein described, assists in the removal of such material and presents an improved step in the carbonization process for the preparation of high grade coke.

At the end of the coking period, the front and rear oven doors are removed and the coke in the chambers is ejected therefrom by the use of pushers in the known manner.

Prior to the pushing operation any layer or 50 film of coke on top of the arches 6B may be converted into gas by the action of steam, preferably highly heated steam, at a temperature of 700 degrees centigrade for example, which may be admitted through those members of the 55 nipples 41 lying vertically above the top of the arches 6B.

After the pushing operation, any coke adhering to the walls of the coking chambers may be burned off by air, preferably heated air supplied 60 from an air preheater (not shown) and admitted from the pipes 45 and conduits 43 through the slits 47. During this process the coking chambers may be "beehived", that is, the holes 42 are opened and the valves 87 (see Figure 8) 65 are closed.

Prior to admitting pitch into the coking chambers as described above, those chambers may be purged of air by blowing steam into the chambers through the slits 47, having previously 70 closed valves 87, and continuing such purging until steam issues freely through the valves 78 (see Figure 8).

The process of the invention, in other forms, may be carried out in other forms of the appa- 75

ratus of the invention, such as, for example, shown in Figures 6 and 7.

Referring to Figure 7, molten bituminous material may be charged through nipples 66A and 67A up to the full or partial capacities of the chambers 70 and 72 and heat applied through the walls of these chambers, to distill and carbonize the bituminous material. The chamber 71 provides a reservoir to receive bituminous material which foams over from the chambers 70 and 72, and which is carbonized in the chamber 71. Moreover, the chamber 71 and the space lying above it and above the structures 61 and 62 provide ample expansion space. Masses of vapor and bituminous material which may more or less rapidly move upward in the relatively narrow chambers 70 and 72 move much more slowly upon reaching the expansion spaces described and such reduction in speed affords opportunity for separation of vapor from the bituminous material. If the chamber 71 is not filled by material from the chambers 70 and 72, additional material may be charged into chamber 71 through the nipples 66B and 67B.

At the close of the coking period, steam, preferably in a highly heated condition, may be directed from the nipples 68 downwardly on top of the structures 61 and 62, and any incandescent coke thereon, to consume the same and convert it into "blue" gas. During such operation, intense combustion may be maintained in the top flues of the structures 61 and 62. The object of this operation is to facilitate the pushing of the coke charge from the chambers 70, 71, and 72 by severing any films or layers of coke which may connect the charges in the chambers 70, 71, and 72.

The soles of the chambers 70, 71, and 72 may be provided with means for admitting steam thereto as hereinabove described.

Referring to Figure 6, the soles 12 of the coking chambers 98 and 99 may be covered with a layer of coke (as hereinabove described) charged through openings 56. Fusible bituminous material is then admitted through nipples 54 and flows down over the highly heated walls of the structure 60. One of the chambers, as 98, is subsequently charged with molten bituminous material up to a height corresponding to that of the highest horizontal partition in the structure 60 while the other chamber 99 is charged only partially. Preferably the extent of free space in the chamber 99, from the top of the structure 60 down to the surface of the bituminous material, is adjusted, by regulating the extent to which the chamber 99 is charged, so that the material which foams over from chamber 98 is equal in volume to the free space described. Additional bituminous material may be added to each chamber or both chambers to make up for shrinkage, so that at the end of the process each chamber is filled with coke, from the sole 12 up to about the middle of the top flue in the structure 60. By application of heat through the walls 57 and walls of the structure 60, the bituminous material is reduced to coke. Vapors and gas are removed and handled as above described, and shown in connection with Figures 2 and 8. At the end of the coking process, highly heated steam is forced through the slits between the soles 12 and adjacent walls and consumes the layer of coke immediately adhering to those walls. Since the steam layer tends to spread out as it rises, a gradually thicker layer of coke will be converted into gas. However, by virtue of the wedge-shaped form of the

coke charge prior to steaming, the final column of coke will be more rectangular in shape than would be the case if the walls of the coking chambers were perpendicular. Since the conversion of coke to blue gas by the action of steam is an endothermic reaction, it is desirable to maintain a high temperature in the flues and heating walls and to use highly heated steam, or other suitable gas.

It is very desirable to maintain pressures in the coking chambers at a value very closely approaching atmospheric pressure in order to facilitate charging the bituminous material into the coking chambers and to prevent leakage of volatile products out of the same.

By providing and maintaining suitable correlation between the capacity of the exhauster 83, the available free space in the condenser 82, the adjustment and operation of the butterfly valve 95 (controlled by the pressure control device 93) and the size of the conduits 77, 79, 81B, 81A, and 81, pressure in the coking chambers and expansion spaces 2A is maintained at a uniform value. By the correlation and coaction of the elements described, increases of pressure are quickly relieved by the exhauster 83 with a minimum of time lag. In other words the gas exhausting and vapor condensing system is responsive in a sensitive manner to the pressure conditions within the coking chambers.

The cooling surfaces in the condenser 82 are preferably so designed as to provide maximum cooling surface together with maximum free space for the vapors passing through the condenser.

To maintain such sensitivity it is necessary to prevent stoppages in the condenser and other gas and vapor conduits and prevent deposits of dirt, soot and solid or viscous condensates from building up therein.

To prevent accumulation of condensates solid at ordinary temperatures, the condensing surfaces of the condenser 82 or of sections thereof are supplied with a cooling medium which has a temperature above the melting or flowing point of the condensate, such as hot water, or steam at atmospheric, super-atmospheric or sub-atmospheric pressures. Such cooling medium is supplied through pipe 85 and withdrawn through pipe 85A. Other condensers (not shown) may be provided and employed in series with the condenser 82 to condense material with lower boiling point range and melting point range than that separated in condenser 82. Instead of separate condensers in series the condenser 82 may be divided into sections (not shown).

The number of condensers or number of sections in a single condenser is influenced by the nature of the bituminous material being carbonized.

Material such as Gilsonite yields in destructive distillation and carbonization distillates containing not only heavy viscous oils but also medium oils and light oil. According to the present invention such distillates are condensed in more than one fraction in different condensers or different sections of the same condenser at different temperatures, so that the normally more viscous or solid condensates are condensed at higher temperatures than the more volatile and less viscous oils and so that the material collecting on the several condensing surfaces readily flows off and such condensing surfaces are maintained clean. On the other hand, certain high melting coal tar residues or pitches yield a distillate substantially free of light oils and such distillate may be con-

dened in one stage by employing warm or hot water or other heated cooling medium.

The special means provided by the present invention for maintaining correct and uniform pressure in the coking chambers is especially necessary in the case of many fusible bituminous materials, such as pitches as distinguished from coals, which pitches, when introduced into highly heated chambers, evolve volatile material more rapidly than is the case with many coals.

The invention provides still further means of maintaining free and quickly responsive communication between the several parts of the by-product and condensing system and preventing the fouling of the condensing surfaces and the contamination of the condensates. This means comprises the chamber 80, in which settling and spraying functions are carried out.

By virtue of the relatively larger cross section 20 of the chamber 80 as compared with that of pipe 81B, the gases and vapors entering the chamber undergo a diminution of velocity and this provides to some extent an opportunity for solid and liquid material to settle out. Furthermore the 25 gases and vapors are subjected to washing by a spray delivered through the nozzle 93. This spray is preferably the oily condensate, or one of the oily condensates condensed in the condenser 82, although numerous other washing 30 media may be employed, including not only liquids but gases, such as for example steam. Impact of the spraying medium against the current of gas from the pipe 81B tends to throw down impurities such as soot or other finely divided particles of 35 carbon and pitch dust or liquid pitch or tar particles, and to prevent such impurities from passing into the condenser.

The word arch as used herein is to be given a broad construction and includes any suitable 40 means of joining walls at the top thereof to accomplish the objects set forth herein.

The coking chambers may have, as shown, a pronounced taper from top to bottom, or a slight taper. They may also taper from end to end, 45 and in such case the chambers are narrower at the pusher end than at the coke discharge end.

Different groups of chambers are charged, coked and discharged at different times and in predetermined rotation. This makes for practical 50 convenience in charging and discharging. Moreover, the volume of gas evolved from any one group of chambers is different at different periods of the coking cycle and by suitably staggering the cycles, the volume and composition of the gas 55 and vapors from a combination of groups is rendered more nearly uniform than would otherwise be the case.

While the description of the preferred form of the process of the invention describes the charging of the ovens with melted bituminous material, it will be understood that the ovens may be charged instead with bituminous material in solid form.

It is also to be understood that various changes 65 may be made in the operations as described herein, and in the form and arrangement of the apparatus without departing from the invention and without going beyond the scope thereof.

What I claim is:

70 1. A coking retort oven, comprising a pair of substantially parallel heating walls spaced horizontally from each other supporting and connected by an arch and forming part of a first heating structure, and enclosing a second pair 75 of substantially parallel heating walls having an

arch at the tops thereof and forming part of a second heating structure which encloses and is braced by partitions forming heating flues within said second heating structure, the walls of the second heating structure being spaced horizontally from the respective walls of the first heating structure thereby partly defining a pair of coking chambers and the respective arches being spaced from each other vertically a distance greater than the horizontal distance between each of the 10 respective walls of the first heating structure and the adjacent wall of the second heating structure, and forming thereby a communicating space between the coking chambers which have soles connecting the walls of the respective heating chambers. 15

2. A structure containing horizontally elongated chambers adapted for the carbonization of fusible bituminous material which comprises, in combination, a plurality of substantially parallel 20 heavy foundation walls spaced horizontally from each other and supporting a plurality of substantially parallel heating walls spaced horizontally from each other and substantially parallel to said foundation walls and containing heating flues, 25 respectively, said heating walls in turn supporting arches which are connected to the heating walls at the tops thereof; the said heating walls and arches partly defining said chambers, a heating partition in each of said chambers extending 30 horizontally from one end of the chamber to the other and from the bottom toward the top thereof and being spaced from the top and from the sides thereof, the heating partitions containing heating flues and being supported on heavy bases which in turn are supported, in part by foundation walls which are spaced horizontally from each other and are substantially parallel and coextensive with the first mentioned heavy foundation walls and are spaced horizontally therefrom, and in 40 part by the latter, the spaces between the respective foundation walls containing regenerators and the spaces between each of the heating partitions and the heating walls adjacent thereto constituting narrow, upright, horizontally elongated 45 coking chambers, each of said coking chambers adjacent each of the heating partitions communicating freely with the coking chamber at the opposite side of the heating partition through the space between the top of the partition and the 50 arch thereabove; and means to communicably connect the flues in the heating walls and heating partitions with the regenerators.

3. A structure as described in claim 2 in which the regenerators on either side and immediately 55 adjacent to each of the first mentioned heavy foundation walls communicate with vertical flues in the said heating walls, the latter being adapted to supply heat to coking chambers adjacent to said heating walls.

4. A structure as described in claim 2 in which the regenerators on either side and immediately adjacent to each of the first mentioned heavy foundation walls communicate with vertical flues in the said heating walls, the latter being adapted 65 to supply heat to coking chambers adjacent to said heating walls, and in which each vertical flue in the said heating walls communicates with both of the said regenerators.

5. A coking retort oven comprising in combination a pair of heating walls which are substantially parallel in a horizontal direction and are spaced horizontally from each other the said walls supporting and being connected at the top thereof by an arch, the said walls and arch partly defining 70

a chamber which is subdivided into a plurality of smaller chambers by partitions each of which comprises a pair of walls spaced horizontally from each other and connected at the top thereof by an arch said walls of said partitions being substantially parallel to said heating walls, the said partitions being spaced from one another and from the first mentioned walls and extending from one horizontal end of the first mentioned chamber to the other end and from the bottom toward the top thereof and being respectively spaced from the top of said chamber, the partitions thus partly defining within the first mentioned chamber a group of coking chambers partly defined by the pair of first mentioned heating walls and the first mentioned arch which is common to and extends over and above all the said coking chambers, each partition containing heating flues, the partitions being mutually connected at the bottom thereof by respective soles and the first mentioned heating walls being connected to the adjacent partitions at the respective bottoms thereof by soles.

6. In a battery of coke ovens, a series of horizontally elongated coking chambers and heating walls therefor alternately arranged side by side in a row, each of said heating walls comprising combustion flues, a vertical partition in each of said coking chambers extending from one end thereof to the other end thereof and from the sole of the coking chamber toward the top of the same and spaced off from the top and lateral sides of the coking chamber, each of the partitions comprising combustion flues.

7. In a battery of coke ovens, a series of horizontally elongated coking chambers and heating walls therefor alternately arranged side by side in a row, each of said heating walls comprising combustion flues, a vertical partition in each of said coking chambers extending from one end thereof to the other end thereof and from the sole of the coking chamber toward the top of the same and spaced off from the top and lateral sides of the coking chamber, each of the partitions comprising combustion flues, the width of the partitions being greater than the width of the chambers between the partitions and the said heating walls.

8. In a battery of coke ovens, a series of horizontally elongated coking chambers and heating walls therefor alternately arranged side by side in a row, each of said heating walls comprising combustion flues, a vertical partition in each of said coking chambers extending from one end thereof to the other end thereof and from the sole of the coking chamber toward the top of the same and spaced off from the top and lateral sides of the coking chamber, each of the partitions comprising combustion flues, the width of the partitions being greater than the width of the chambers between the partitions and the said heating walls, said flues being horizontal communicating passageways between successive horizontal cross walls situated in the said partitions and joined with the vertical walls thereof, whereby the said partitions are internally braced and are provided with a plurality of horizontal communicating combustion flues.

9. A structure as in claim 8 in which the said horizontal combustion flues are each provided with gas supply nozzles controllable from a position outside of the coking chambers and are in communication with regenerators located beneath the said partitions.

10. In a battery of coke ovens, a series of horizontally elongated coking chambers and heating walls therefor alternately arranged side by side in a row, each of said heating walls comprising combustion flues, a vertical partition in each of said coking chambers extending from one end thereof to the other end and from the sole of the coking chamber toward the top of the same and spaced off from the top and lateral sides of the coking chamber, the distance between the top of the partition and the top of the said coking chamber being greater than the lateral distance between the said heating walls and the partition, each partition containing internal bracing partitions and heating flues between said internal bracing partitions.

11. A group of substantially parallel, upright, horizontally elongated coking chambers, this group being enclosed and partly defined by heating walls and an arch supported thereby, the said heating walls being substantially parallel in a horizontal direction, the said chambers being separated by at least one partition horizontally elongated and substantially parallel to the said heating walls, which partition contains heating flues and extends from the bottom of the chambers toward the arch and is spaced vertically therefrom, the said chambers freely communicating with each other through a common space under the said arch and above the said partition, which space is defined in part by the interior surface of said arch, the distance along a vertical line from the top of the partition to the said surface of the arch being greater than the width of the respective chambers.

12. Apparatus for coking bituminous material rendered substantially entirely liquid at coking temperatures comprising side walls, a top wall and a substantially imperforate floor defining a substantially horizontal coking chamber, a heating wall within and extending entirely through said coking chamber in a horizontal direction, said heating wall also extending from the floor of said coking chamber toward but not entirely to the top thereof, said heating wall and said top wall forming a passage permitting flow of said bituminous material over said heating wall during the coking operation, means for passing hot gases through said heating wall to heat said bituminous material, and additional means for imparting heat to said bituminous material, said chamber being provided with a closure through which the charge of coke may be directly removed substantially in block in a horizontal direction.

13. Apparatus for coking pitch comprising substantially vertical side walls, a top wall and a substantially imperforate floor defining a horizontal coking chamber, a heating wall provided with a plurality of flues within and extending entirely through said coking chamber in a horizontal direction, said heating wall extending from the floor toward but not entirely to the top of said chamber, thereby dividing said chamber into two portions connected at their tops by a passage permitting flow of pitch from one of said portions to the other, means for passing hot gases through the flues of said heating wall to heat said pitch and additional means for heating said pitch, said chamber being provided with a closure through which the charge of coke is directly removed substantially in block in a horizontal direction.

JOSEPH V. MEIGS.
